CLAIM

The ornamental design for a vegetable cutter, as shown and described.

DESCRIPTION

FIG. 1 is a front perspective view of a vegetable cutter, showing my new design in an open state of use;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the vegetable cutter in a closed state;

FIG. 10 is an enlarged detail view of area 10 in FIG. 1 thereof;

FIG. 11 is an enlarged detail view of area 11 in FIG. 2 thereof; and,

FIG. 12 is an enlarged detail view of area 12 in FIG. 3 thereof.

The broken lines in the drawings illustrate the portions of the vegetable cutter, which form no part of the claimed design. The dash-dot-dash broken lines encircling the enlarged views are for annotative purposes only and form no part of the claim thereof.
